(57) **CLAIM**

The ornamental design for an electronic portable device with a graphical user interface, as shown and described.

DESCRIPTION

FIG. 1 is a front view of an electronic portable device with a graphical user interface showing a first image in a sequence;

FIG. 2 is a front view of a second image thereof;

FIG. 3 is a front view of a third image thereof;

FIG. 4 is a front view of a fourth image thereof; and,

FIG. 5 is a front view of a fifth image thereof.

The appearance of the transitional image transitions between the images shown in FIGS. 1-5. The process or period in which one image transitions to another image forms no part of the claimed design.

In the drawings, the dash-dot-dot lines showing an electronic portable device with a graphical user interface depict environment and form no part of the claimed design. The dash-dot-dot lines define the bounds of the claimed design and form no part thereof.
